(57) **CLAIM**

The ornamental design for a waterproof phone case, as shown and described.

DESCRIPTION

FIG. 1 is a perspective view of a waterproof phone case showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof.

FIG. 9 is a perspective view thereof showing the grip in an extended state;

FIG. 10 is another perspective view thereof showing the grip in an extended state;

FIG. 11 is a front view thereof showing the grip in an extended state;

FIG. 12 is a rear view thereof showing the grip in an extended state;

FIG. 13 is a left-side view thereof showing the grip in an extended state;

FIG. 14 is a right-side view thereof showing the grip in an extended state;

FIG. 15 is a top view thereof showing the grip in an extended state; and,

FIG. 16 is a bottom view thereof showing the grip in an extended state.

The broken lines illustrate portions of the waterproof phone case that form no part of the claimed design.

1 Claim, 16 Drawing Sheets
